UNITED STATES PATENT OFFICE.

LAURENS P. DIXON, OF NEW YORK, N. Y.

SPARK-PLUG.

1,191,162.

Specification of Letters Patent.

Patented July 18, 1916.

Application filed September 11, 1914. Serial No. 861,177.

To all whom it may concern:

Be it known that I, LAURENS P. DIXON, a citizen of the United States, and a resident of New York, borough of Manhattan, 5 county and State of New York, have invented certain new and useful Improvements in Spark-Plugs, of which the following is a specification.

This invention relates to what are known 10 as spark-plugs for internal combustion motors, with more particular reference to the casings thereof.

It is well known that among the difficulties which have heretofore been encountered 15 in connection with spark-plug ignition systems are those of overcoming conditions which result in short-circuiting, due either to the accumulation of carbon or other foreign matter on the points of the terminal 20 electrodes, or to the accumulation of oil, grease or even water, with possibly a certain amount of soluble or insoluble matter, forming a coating on the exterior of the insulator and the exposed parts of the plug. With interior short-circuiting, the present invention 25 has nothing to do, other than to provide a construction which embodies the best of well-known principles in a simple, compact, efficacious and dependable manner, the principal 30 object of this invention being the provision of a spark-plug and casing so constructed as to minimize exterior short-circuiting. Incidental to the above, although hardly less important from a commercial view-point, I have in view the provision of a casing or insulator which may be attached or secured to any of the better-known types of standard spark plugs without alteration in construction or design thereof.

My invention will be readily understood by reference to the accompanying drawings, forming a part of this specification, in which—

Figure 1 is a side elevation of a spark plug embodying my invention; Fig. 2 is a central sectional elevation of the same; Fig. 3 is a top plan view thereof; Fig. 4 is a transverse section taken substantially on the line 4—4 of Fig. 2; Fig. 5 is a fragmentary 50 elevation of the casing with its retaining sleeve-gland, the inclosed insulator and the central electrode, as hereinafter described in detail, and Fig. 6 is a vertical central section of the upper part of a plug showing 55 a modification of the preferred form of my invention.

Referring now to the drawings in detail, numeral 10 designates the body portion of a casing of preferably cylindrical form, which is molded from any desired self-hardening plastic material possessing, when set and dry, and possibly glazed, the essential qualities of high electrical resistance, high caloric resistance and a high degree of water resistance, of which materials or compounds 60 there are many well-known kinds. This body portion 10 of the casing is designed to be molded directly on the upper end of the sleeve-gland 11, which is provided with a preferably integral upwardly-projecting L-shaped 65 collet 12 around which said casing is molded to form a permanent and tight connection. This permanent union between casing and sleeve-gland forms one of the important elements of my invention.

The usual porcelain insulator 13 is of common and well-known design, projecting in the usual manner down into the preferably rust-proof steel body 14, where it is provided with an enlarged portion 15 forming 80 annular shoulders adapted to be clamped between an interior shoulder on the body 14 and the lower end of the sleeve gland 11 which is screwed into said body, through the interposition of suitable packing rings 85 16—16—a common and well-known arrangement and construction. This insulator 13 is provided with the usual central bore through which projects the conductor-rod or central electrode 17, which is provided in 90 the usual manner with the enlarged portion 18 and is screw-threaded at its upper end for the reception of the retaining nut 19, whereby said electrode may be permanently and rigidly secured in said insulator.

The casing 10 is suitably apertured for the reception of the insulated wire 20 which leads from whatever source of electric energy may be employed, the aperture proper being formed by the reduced portion of a comparatively large bore 21 to which I prefer to give increased length through the provision of a boss 22 on the side of the casing. The larger portion of this bore forms a pocket or recess for the reception of a flexible washer 23 snugly fitted on the insulated wire 20 and slightly greater in diameter than the diameter of the bore 21. I prefer to make this washer of ordinary commercial soft rubber, whereby, when said washer is 100 mounted on the wire, with a central hole 105 slightly less in diameter than the diameter

of the wire 20, said washer is slightly distorted and assumes a cup-shaped contour, this distortion being augmented by forcing said washer into the bore 21, the edges thereof of pressing against the side walls of the bore and thus forming a water-tight connection between said wire and said casing. It will be noted that the contour of this washer after distortion is such that it will readily 10 resist exterior fluid pressure and prevent the ingress of fluids and foreign matter to the interior of the casing, and yet will readily yield to internal pressure should any of the expanding gases force their way into the casing. The exposed end of the terminal of the wire 20 is looped around the rod 17, above the nut 19, in the usual manner, and preferably clamped thereto by means of a sleeve 24 which is interiorly screw-threaded 15 to mesh with the threads at the upper end of said rod. I have shown this sleeve provided with a slot at its upper extremity for the reception of the edge of the blade of a screw-driver, or other suitable tool, to facilitate manipulation of said sleeve and secure proper electrical connection between the wire and the central electrode.

The body portion 10 of the casing is provided with a cap 25 of the same material or 30 composition, the upper end of said body portion being preferably interiorly recessed or notched and said cap being provided with a boss or enlarged major middle portion telescoping and fitting in said recess to form, in connection with a suitable packing ring or gasket 26, a more nearly fluid-tight joint. Into this cap 25 is molded the nut 27, interiorly threaded to mesh with exterior threads on the sleeve 24. It will be apparent 35 that after the interior electrical connection has been made between the wire 20 and the rod 17, the cap 25 may be screwed down in place, this operation not only serving to effect the sealing of the casing against the 40 ingress of foreign matter, but also performs the function of a lock or jam nut to more tightly bind or clamp the terminal of wire 20. I have shown the cap 25 milled for the 45 purpose of facilitating manipulation thereof by hand.

In Fig. 6, I have shown a slight modification of the preferred form of my invention. In the preferred construction, as shown in Fig. 2, I am employing the sleeve 24 merely 50 for the purpose of facilitating the making of the electrical connection, but it will be apparent that I may, if I desire, employ a nut 30 (Fig. 6) coöperating with the nut 19 in the usual manner to establish the electrical connection, and make the interior threads of the nut 27' mesh with the threads of the upper portion of the electrode 17, thus establishing a direct connection therewith to secure the cap 25 firmly and tightly in place. This construction is somewhat simpler than

that shown in the other figures of the drawings, although possibly not so easy to assemble and adjust.

The body 14 is designed to be screwed into the cylinder of the motor in the usual manner, and carries at its extremity the terminal electrodes 28 28, the points of which are brought into proximity with the terminal 29 of the central electrode to provide spark gaps of proper dimensions.

With respect to my invention, it will be apparent that I have provided a spark-plug which is so incased as to practically eliminate all possibility of exterior short-circuiting. While this frequently results from deposits of oil and grease in motors designed for any purpose, it is particularly prevalent in connection with marine motors where spray, fog and even high humidity may cause short-circuiting through a thin coating 85 of water over the ordinarily exposed parts of the plug.

I claim as new and desire to secure by Letters Patent:

1. In a spark-plug, the combination, with 90 a gland connecting the metal body and the insulator for the central electrode, of an exterior shell consisting entirely of insulating material, said shell including a removable cap and completely incasing and 95 exteriorly insulating the feed-wire connections.

2. In a spark-plug, the combination, with 100 a gland connecting the metal body and the insulator for the central electrode, of an exterior shell consisting entirely of insulating material rigidly secured to said gland, said shell including a removable cap of the same material and the whole completely incasing and insulating the feed- 105 wire connections.

3. In a spark plug, the combination, with 110 a gland connecting the metal body and the insulator for the central electrode, of an exterior shell consisting entirely of insulating material carried by said gland, said shell including a removable sealing cap and the whole forming a shell completely incasing and insulating the feed-wire connections, and said cap being rigidly held in 115 place through the medium of said central electrode.

4. In a spark-plug, the combination, with 120 a gland connecting the metal body and the insulator for the central electrode, of an exterior insulating casing of self-hardening plastic material molded upon said gland, said casing including a cap of similar material and said cap including means for interiorly securing the same in place.

5. In a spark-plug, the combination, with 125 a gland connecting the metal body and the insulator for the central electrode, of an exterior insulating casing of self-hardening plastic material molded upon said gland,

- said casing including a cap of similar material and said cap having molded therein a nut for securing the same in place through the medium of the central electrode.
- 5 6. In a spark-plug, the combination, with a gland connecting the metal body and the insulator, of an exterior insulating casing secured to said gland, said casing including a removable sealing cap, a central electrode
- 10 threaded at its upper end for the reception of the retaining nut and an interiorly threaded sleeve coöperating with said nut to clamp the wire terminal therebetween and establish an electrical connection, said sleeve
- 15 being also exteriorly threaded to receive a cap-retaining nut secured within said cap.
7. In a spark-plug, the combination, with a gland connecting the metal body and the insulator, of an exterior casing of self-hardening plastic material molded upon said gland, said casing including a cap of similar material, a central electrode threaded at its upper end for the reception of the retaining nut and an interiorly threaded
- 20 sleeve coöperating with said nut to clamp the wire terminal therebetween and establish an electrical connection, said sleeve being also exteriorly threaded to receive a cap-retaining nut around which said cap is
- 25 molded.
8. In a spark-plug, the combination, with the interinsulated conductors to the terminals at the spark gap, of an exterior shell consisting entirely of insulating material completely incasing the feed-wire connections, a portion of said shell being removable to permit access to the interior thereof without disturbing said connections.
9. In a spark-plug, the combination, with
- 40 the interinsulated conductors to the termi-

nals at the spark gap, of an exterior insulating shell completely incasing the feed-wire connections, said shell being provided with an aperture for the insertion of the feed-wire terminal, and a washer of yielding material on said terminal of such dimensions as to be distorted when forced into said aperture.

10. In a spark plug, the combination, with the interinsulated conductors to the terminals at the spark gap, of an exterior insulating shell completely incasing the feed-wire connections, said shell consisting entirely of insulating material and being provided with an aperture for the insertion of the feed-wire terminal, and a washer of yielding material on said terminal of such dimensions as to be distorted when forced into said aperture.

11. In a spark plug, the combination, with the interinsulated conductors to the terminals at the spark gap, of an exterior insulating shell completely incasing the feed-wire connections, said shell consisting entirely of insulating material and a portion thereof being removable to permit access to the interior of said shell, and said shell being provided with an aperture for the insertion of the feed-wire terminal, and a washer of yielding material on said terminal of such dimensions as to be distorted when forced into said aperture.

In testimony of the foregoing, I have hereunto set my hand in the presence of two witnesses.

LAURENS P. DIXON.
